(57) **CLAIM**

We claim the ornamental design for a slide top pocket scale, as shown and described.

DESCRIPTION

FIG. 1 is a front elevation view of a slide top pocket scale of the present invention.

FIG. 2 is a back elevation view of the scale shown in FIG. 1.

FIG. 3 is an elevation view from the right side of FIG. 1.

FIG. 4 is an elevation view from the left side of FIG. 1.

FIG. 5 is a top plan view of the scale shown in FIG. 1.

FIG. 6 is a bottom plan view of the scale shown in FIG. 1; and,

FIG. 7 is a perspective view of the scale as viewed from the lower right of FIG. 1, with the slide top moved to reveal a weighing surface.
